UNITED STATES PATENT OFFICE.

ADOLF DOWALD, OF BREMEN, GERMANY.

ROLLER FOR SLIDING DOORS AND THE LIKE.

1,414,630.

Specification of Letters Patent. Patented May 2, 1922.

Application filed September 2, 1919. Serial No. 321,268.

(GRANTED UNDER THE PROVISIONS OF THE ACT OF MARCH 3, 1921, 41 STAT. L. 1313.)

To all whom it may concern:

Be it known that I, ADOLF DOWALD, manufacturer, a citizen of Germany, residing at and whose post-office address is Bremen, 5 Schleifmühle 72, Germany, have invented certain new and useful Improvements in Rollers for Sliding Doors and the like, (for which I have filed applications in Germany July 18, 1918, and patented July 20, 1920, 10 No. 323,334, and in Germany Mar. 6, 1919, patented July 20, 1920, No. 323,335;) and I do hereby declare the following to be a full, clear, and exact description of the invention, such as will enable others skilled 15 in the art to which it appertains to make and use the same.

This invention relates to devices for facilitating the shifting of sliding doors and the like, in which a ball-shaped or wheel-shaped 20 roller, on which the door slides, revolves in a ball bearing.

An object of the invention is to simplify and cheapen the manufacture of this kind of roller, and to improve their construction so 25 as to lessen or overcome the troubles due to jamming, and thus to decrease the likelihood of violence being used in opening or closing the sliding door.

This object is accomplished by attaching 30 to the fastening iron, by which the complete roller is fixed to the door, a block into which a round hole, for the reception of the ball-shaped or wheel-shaped roller and its bearing balls, is made to a certain depth, so as 35 to leave an unperforated back, the hole being closed after the insertion of the roller and its bearing balls, and a slot being made in the block into which the bar fits along which the door slides. The block may be cast in 40 one piece with the fastening iron, or formed with it in a rolling process, or it may be welded or fixed thereto in any other adequate manner. The new device is suitable for doors which are suspended from above 45 by the sliding rollers, and also for doors that rest upon roller arranged at the bottom.

The arrangement and design of the parts 50 of the new roller make it easy and cheap to manufacture, because it is only necessary to make a simple cylindrical hole in the solid block, which latter may be an integral part of the fastening iron. No special bearing rings or bushes are required for the weight

carrying balls. The assembling of the complete roller is thus made very easy to carry 55 out.

In the known forms of rollers which have been provided with ball bearings for the purpose of rendering the movement of sliding doors as frictionless as possible, the vertical pressure only was made to be taken up by the bearing balls. When lateral, horizontal pressure occurs, which is sure to happen when the door jams, the end surfaces of the rollers of the present kind are bound to 60 rub, or, if ball-shaped rollers are used, they will be jammed fast, so that in any case sliding friction, instead of rolling friction, will take place, and the door will be difficult to move. With the new arrangement, a type 70 of ball-bearing for the travelling roller or ball results in which the carrying balls, i. e. the balls forming the bearing, take both the vertical and the horizontal bearing pressures and transfer them to the walls of the device 75 without the travelling ball or roller coming into contact with the said wall. The whole horizontal pressure on the bearing is transferred in a direction vertical to the surfaces over which the balls roll. 80

Several ways of carrying out the inventions are shown in the drawing in which,

Fig. 1 is a vertical section through a roller taken at right angles to the face of the door,

Fig. 2 is a vertical section through Fig. 1 85 taken parallel to the face of the door, and

Fig. 3 is a horizontal section.

Fig. 4 illustrates a modification in which a travelling roller is used instead of a ball.

Figs. 5 to 8 represent various forms of 90 travelling rollers.

Fig. 9 illustrates a design which provides for the removal of the roller casing or block from the fastening iron.

Similar parts have like signs of reference 95 in all of the figures.

In the drawing *a* denotes the track or track bar which has an L-shaped section in the illustrated designs, but which may be made in any desired shape. In Figs. 1 to 3, 100 *b* is the travelling ball, and in the other figures the travelling roller, that revolves between the bearings formed by the carrying balls *c* and *d*. *e* is the fastening iron, which may be made from one piece with the block 105 *f*, and may be shaped in the form of an

angle, a flat bar, or otherwise, according to the manner in which the roller is to be fastened to the door *o*.

A cylindrical hole *m* is drilled to a certain depth in the block *f* so that a back wall *k* (Figs. 1, 2 and 3) remains. The bottom wall of the casing, that results from the drilling of the hole *m*, is provided with a slot *g* through which the track bar *a* is inserted so as to allow the ball *b* to roll upon it.

To assemble the parts of the roller the casing *f*, which has been fashioned from the solid block, is laid with the outer surface of its back wall *k* downwards and then the ring of balls *d* is placed on the inner surface of the said wall.

Then the travelling ball or roller *b*, and finally the second ring of carrying balls *c* is inserted. The front opening of the casing is then closed by a plate *h* which, as is indicated by broken lines in Fig. 2 and in the horizontal sectional representation of Fig. 3, may take the form of a wedge-shaped slide with bevelled edges fitting into bevelled grooves that is held in place by screws in the holes *i*.

After the hanging or bearing iron *e*, to which the block *f* is attached, has been fixed to the top or bottom of the door as the case may be, the roller is lifted onto the track bar *a* and by means of a stop *p*, which is fixed by screws, it is prevented from being shifted off the bar by lifting.

An advantage gained by employing the rollers shown in Figs. 4 to 8, instead of the ball *b* represented in Fig. 1, is that the upper edge of the track bar *a* is not hollowed out as in Fig. 1, but may be made flat (Figs. 5 and 8) or arched (Figs. 4 and 7) or roof-shaped as in Fig. 6. By this means the accumulation of water on the track of the roller, which would occur if the door were exposed to the weather, is prevented.

As may be seen from Figs. 1 and 2 the hole in the block *f* is preferably positioned so as to make the shell of the casing, thicker at the top than at the bottom, so that the thicker wall is that which bears the load.

The milling of the slot *g* is preferably done after the drilling operation.

In the modification shown in Fig. 9 the block *f* is detachable from the hanging or

bearing (tension on pressure) iron. By this arrangement the whole roller comprising the travelling roller or ball with its bearing balls 55 may easily be removed from the door for repairs whenever any trouble due to breakage of balls or other mishaps arises. This is of special importance in cases of heavy, 60 large doors or gates.

In this Fig. *a* again represents the track bar and *b* the travelling roller which is journaled between the carrying or bearing balls *c* and *d*. Into an opening in the hanging or bearing iron *e* the block *f* is inserted 65 in which latter a cylindrical hole *m* and a slot *g* for the track bar is made. The hole *m* of the block *f* is closed by the plate *h*.

The exterior of the block *f* may be of any desired shape such as circular, square, oval, 70 etc. It may also be fixed in the fastening iron *e* by any suitable means such as a screw *n*.

I claim:

1. In a roller device for a sliding door, or 75 the like, a block having a cylindrical cavity and a lateral slot, a rear wall at one end of said block and integral therewith, and a lid for covering the other or open end of said block.

2. In a roller device for a sliding door, or the like, a housing for the roller bearing consisting of a single block comprising a chamber for containing the rollers and a lid constituting the end wall for said chamber, the 85 other walls of the chamber being integral with said block.

3. In a roller device for a sliding door, or the like, comprising a track, a housing for the roller bearing comprising a single block, 90 a cylindrical chamber within the block, said chamber opening at one end of the block for admitting the bearing rollers, a lid for closing the open end of said chamber, and a lateral slot in the wall of said chamber for 95 admitting the track into contact with said rollers.

In testimony whereof I affix my signature, in presence of two witnesses.

ADOLF DOWALD.

Witnesses:

JULIUS ENGSTFELD,
CHRISTAIN HISCHE.
